O. R. ERWIN

PAIL EXTINGUISHER

Filed Dec. 10, 1920

UNITED STATES PATENT OFFICE.

ORLANDO R. ERWIN, OF FOREST HILLS, NEW YORK, ASSIGNOR TO FOAMITE-CHILDS CORPORATION, OF NEW YORK, N. Y., A CORPORATION OF DELAWARE.

PAIL EXTINGUISHER.

Application filed December 10, 1920. Serial No. 429,659.

To all whom it may concern:

Be it known that I, ORLANDO R. ERWIN, a citizen of the United States, and resident of Forest Hills, in the county of Queens and 5 State of New York, have invented certain new and useful Improvements in Pail Extinguishers, of which the following is a specification.

This invention relates to improvements 10 in a fire extinguishing device, and more particularly to an apparatus designed for use in connection with extinguishing of fires by manual manipulation of a vessel carrying the component solution of an extinguishing 15 medium, and has special reference to an improved fire extinguishing vessel of the type described in the patent to Meigs, No. 1,287,- 388 of December 10, 1918.

In the type of fire extinguishing device 20 described in the patent referred to, use is made of two concentrically mounted receptacles, both open at one end, the receptacles defining an inner central compartment and an outer annular compartment, the said 25 compartments holding respectively an acid and a basic solution, these comprising component solutions which are adapted to be commixed in the event of fire to produce a fire extinguishing foam, the commixture being effected by dashing the solutions through the 30 open ends of the receptacles and towards the fire to be extinguished. In this fire extinguishing device the inner receptacle comprises a container made of copper which is 35 tinned to withstand the corroding effect of the acid solution held by the container, the receptacles being held in fixed relative positions by means of threaded members formed in the bottoms thereof.

40 It has been found that the cost of producing a fire extinguishing device of the type referred to is relatively large, due principally to the cost of manufacturing the inner receptacle; the sheet copper of 45 which such receptacle is made being relatively expensive and the cost of making a receptacle therefrom having a bottom provided with a threaded female member, the whole undergoing further tinning treatment to produce a non-corroding container, being relatively high, this large production cost preventing the extensive adoption of 50 this type of extinguisher consistent with its established and well recognized utility. It

has been further found that this expensive 55 tinned copper container could be effectively replaced by an ordinary glass jar, means being supplied to removably retain the glass jar in the outer receptacle, the glass jar more effectively functioning to withstand 60 corrosive action of the acid and reducing the cost of production of the device to a fraction of its previous cost.

The principal objects of my present invention therefore involve, in addition to the 65 provision of an improved fire extinguishing device of the nature referred to, having in view the production of a simple, a more efficient and more inexpensive vessel; the provision of an inner container to replace 70 the expensive metallic inner container used prior to my invention; the provision of such inner container which will more effectively withstand corrosive action of the acid solution contained therein; and the further 75 provision of improved and easily assembled means for removably retaining the inner container within the outer receptacle.

To the accomplishment of the foregoing and such other objects as may hereinafter 80 appear, my invention consists in the elements and their relation one to the other, as hereinafter particularly described and sought to be defined in the claims, reference being had to the accompanying drawing 85 which shows a preferred embodiment of my invention and in which—

Figure 1 is a cross sectional elevational view of the fire extinguishing device, and

Figure 2 is a plan view thereof.

90

Referring to the drawing, the outer container comprises preferably a tapered body portion 5 of the usual pail type and a bottom 6 connected to the body portion 5 in any approved manner, as by the interlocking sealed connection 7, the bottom 6 having an annular bead 8 struck up from the metal from which the bottom is made; this bead defining a seat for the reception of the inner container 9, as shown clearly in the 100 drawing. This inner container 9 is intended for holding the A or acid solution, the annular compartment between the inner and outer containers being intended for the B or basic solution, this inner container 9 being preferably centrally located with respect to the outer container and being mounted as shown in the figures and re-

95

100

105

ceived by the annular bead 8, this bead preventing any radial motions of the inner container with respect to the outer container.

5 For the purpose of more effectively withstanding the corrosive action of the acid solution held by the inner container and for the further purpose of producing a more inexpensive vessel and doing away with the 10 tinned copper container of the patent to Meigs, the receptacle 9 of my invention comprises a vitreous container and more particularly an ordinary glass jar. This jar may be produced at a very low cost as is well known 15 and the use of such a jar in this fire extinguishing vessel reduces the production and therefore the selling cost to a fraction of its previous cost.

For the purpose of retaining the glass 20 jar 9 within the outer container and for preventing any radial or axial motion of the glass jar with respect to the outer container, simple means is provided which may consist of a strip of metal 10 bent on an intermediate portion thereof to provide opposed V-shaped portions 11 adapted to be mounted over opposed portions of the side walls of the container 9, the interengagement of the crook of the V and the rim of the 25 container 9 permitting a relative rotation of the strip of metal 10 with respect to the inner container 9, the crook of the V riding on the rim of the container during such relative rotation. Strip 10 is provided at its outer 30 ends with upturned portions 12, these upturned portions being adapted to be received by straps 13 fitted to the inner surface of the outer container at opposed sides thereof, these straps being secured to the 35 container by means, for example, of rivets 14, these rivets also serving the purpose of securing the bail clips 15 to the outer surface of the outer container at opposed ends thereof. The strip 10 may be made of any 40 desired material, preferably of metal, which will be effective to retain the inner container 9 in position and which will permit a resiliency of the outer portions of the strip so that the outer portions may be bent 45 downwardly when the parts of the device are to be assembled or disassembled, the downward motion of the ends of this strip permitting the upturned portions 12 to be removed from the retaining straps 13, the 50 strip 11 being then rotated and removed from the vessel, thereby permitting the removal of the inner container 9 from the outer receptacle 5. The vessel is provided with the usual bail 16 and with the usual cover 55 (not shown).

The manner of assembly of the parts and use and operation of the device will be apparent from the above description thereof.

In assembling the parts, the outer container 60 5 may first be supplied with the B or basic

solution and the inner container 9 holding the A or acid solution may then be inserted in the outer container; the bottom of the inner container being received by the struck up annular seat 8. The strip 10 is then inserted with the V portions 11 fitting over the rim of the inner container and with the upturned portions 12 out of alinement with the openings provided by the straps 13. The outer portions of the strip are then urged 70 downwardly, the strip being then rotated on the glass jar until the upturned portions 12 are in alinement with the opening provided by the straps 13. Release of pressure on the outer portions of the strip permits the upturned portions 12 to enter the said openings as will be obvious; further 75 upward motion of the strip being prevented by the engagement of the strip with the front wall of the strap and circumferential motion of the said strip being also prevented by the confinement of the upturned portion 12 by the side walls of the said strap 13. It will be obvious that this simple means 80 not only secures the inner container in position relatively to the outer container during ordinary storage use, but permits the confinement of the inner container during 85 operation of the vessel as a fire extinguishing device. In the event of fire, the vessel 90 is grasped in the ordinary way and the component solutions held by the inner and outer containers respectively are dashed on to the fire, commixture of the solutions taking place 95 during the passage thereof from the open 100 ends of the containers to the point of application, namely the fire, this commixture resulting in the generation of the fire extinguishing foam which acts as a fire extinguishing medium. When renewal of the 105 charge is necessary, as, for example, when deterioration of the solutions effected by time results, or when cleaning of the vessel is desired, the parts may be disassembled 110 in a simple manner, the end portions of the strap being urged downwardly and the strap rotated until the upturned portions 12 are out of alinement with the straps, the strip 10 being then removed, permitting the removal of the inner container 9 by a simple 115 upward movement of the said container 9.

It will be apparent from the above that I have provided an improved fire extinguishing device of the manually manipulable vessel type which will reduce the vending cost to a minimum to permit more extensive use of this type of fire extinguishing means, providing at the same time a vessel which will withstand the corrosive action of the solutions employed; providing furthermore, parts which may be easily manufactured and which may be assembled in a very facile manner.

While I have shown my device in the preferred form, it will be obvious that many 120 125 130

changes and modifications may be made in the structure disclosed without departing from the spirit of the invention, defined in the following claims.

5 I claim:

1. A fire extinguisher pail comprising inner and outer open top receptacles defining a central compartment and an annular compartment surrounding the central compartment for holding separate chemical component solutions which upon commixture produce a fire extinguishing agent, and means for supporting the inner receptacle in said outer receptacle comprising provisions having attachment to said outer receptacle and having means for engaging the rim of the inner receptacle, the construction of the receptacles being such that the component solutions may be simultaneously projected from the pail by a manual dashing or dumping action whereby to cause said components to intermix after leaving the pail and produce the fire extinguishing agent.

2. A fire extinguisher pail comprising inner and outer open top receptacles defining a central compartment and an annular compartment surrounding the central compartment for holding separate chemical component solutions which upon commixture produce a fire extinguishing agent, and means for supporting the inner receptacle in said outer receptacle comprising provisions having attachment to said outer receptacle and having means for engaging the rim of the inner receptacle and adapted to bear axially upon the same to prevent outward motion of the said inner receptacle during dumping or dashing action of the solution content of the pail.

3. A fire extinguisher pail comprising an outer receptacle, an inner vitreous receptacle, the said receptacles defining a central compartment and an annular compartment surrounding the central compartment for holding separate chemical component solutions which on commixture produce a fire extinguishing agent, and means for supporting the vitreous receptacle in the outer receptacle comprising movable resilient provisions having attachment to said outer receptacle and having means for engaging the rim of the inner receptacle, the construction of the receptacles being such that the component solutions may be simultaneously projected from the pail by a manual dashing or dumping action whereby to cause said com-

ponents to intermix after leaving the pail and produce the fire extinguishing agent.

4. In a fire extinguishing device, a manually manipulable pail comprising concentrically mounted inner and outer receptacles, said receptacles having open tops and both defining a central compartment and an annular compartment surrounding the central compartment for holding separate chemical component solutions which upon commixture produce a fire extinguishing agent, and means for supporting the said inner receptacle in the outer receptacle comprising an annular seat formed in the bottom of the outer receptacle for receiving the bottom of the inner receptacle, and an element removably mounted at the open top of the outer receptacle and provided with means for engaging the rim of the inner receptacle.

5. A fire extinguishing device comprising an outer open top receptacle having an annular seat in its bottom, and bail clips mounted on the exterior at the top thereof, straps mounted on the exterior of the receptacle and in alinement with the bail clips, the clips, and the straps being fixed to the container by unitary attaching means, an inner open top receptacle with its bottom received by the said annular seat, and a removable resilient element for removably retaining the inner receptacle in position in the said outer receptacle, said element having means for engaging the open top of the said inner receptacle and having means engageable by the said straps.

6. A fire extinguishing device comprising an outer open top receptacle having an annular seat in its bottom, and bail clips mounted on the exterior at the top thereof, straps mounted on the interior of the receptacle and in alinement with the bail clips, the clips and the straps being fixed to the container by unitary attaching means, and an inner open top receptacle made of vitreous material with its bottom received by the said annular seat, and a removal resilient element for removably retaining the inner receptacle in position in the said outer receptacle, said element having means for engaging the open top of the said inner receptacle and having means engageable by the said straps.

Signed at New York in the county of New York and State of New York this 3rd day of December A. D. 1920.

ORLANDO R. ERWIN.
